UNITED STATES PATENT OFFICE.

CHARLES F. KRAUT, OF BALTIMORE, MARYLAND, ASSIGNOR TO THE KRAUT SAFETY VALVE COMPANY, OF BALTIMORE, MARYLAND, A CORPORATION OF MARYLAND.

SAFETY-VALVE.

1,271,726.

Specification of Letters Patent.

Patented July 9, 1918.

Application filed August 29, 1917. Serial No. 188,860.

To all whom it may concern:

Be it known that I, CHARLES F. KRAUT, a citizen of the United States, residing at Baltimore and State of Maryland, have invented certain new and useful Improvements in Safety-Valves; and I do declare the following to be a full, clear, and exact description of the invention, such as will enable others skilled in the art to which it appertains to make and use the same.

The present invention has for its principal object to improve upon the construction and mounting of the valve ring illustrated in my U. S. Patent 1217316 of February 27, 1917, it being intended that greater space shall exist between the ring and its spring-pressed seating member to allow the steam to escape more easily, so that the ring will not be unseated an excessive amount, that said ring shall be stiffened against warping or springing from the steam pressure, and that the stiffening means shall coact with the external webs on said seating member to center the ring without securing it to said member.

Another object is to so improve upon the structure of the old device, as to confine a larger body of steam close to the valve ring, without increasing the area of the latter upon which the steam acts.

Yet another object is to decrease the labor and expense necessary in manufacturing the patented device and in making repairs after installation.

These objects are carried out by the novel features of construction and unique arrangements of parts hereinafter fully described and claimed, the descriptive matter being supplemented by the accompanying drawings which form a part of this specification and in which:

Figure 1 is a vertical section of the improved valve, partly in elevation;

Fig. 2 is a horizontal section of Fig. 1 on the plane of the line 2—2 thereof; and

Fig. 3 is a partial bottom plan view.

In the drawings above briefly described, the numeral 1 has reference to a valve casing preferably disposed vertically and having a steam passage 2 threaded at its inlet end for attachment to the boiler. Positioned within the outlet end of the passage 2 is a cup-like guide 3 which is held centered therein by radial arms or webs 4 cast inte-

grally with both parts. It will be observed that the guide 3 necessarily obstructs a portion of the delivery end of the passage 2, so that an annular steam discharge space 5 is provided, and in order that a large volume of steam may be confined adjacent the valve ring 6, without increasing the area of the latter upon which the steam acts, the inlet portion of the space 5 is preferably increased in width as indicated at 7. It is desirable to avoid having obstructions in the steam discharge space such as would divert the flow of steam from a straight course through said space and impede its escape by causing it to take a tortuous course. To this end, the inner wall of the passageway 1 is cylindrical, and is reduced in diameter at its upper end to form the outer wall of the steam discharge space 5, and the outer peripheral wall of the guide 3 is reduced in diameter below the discharge space 5, the opposed walls of the passageway and guide below said space being thus out of line with the walls of the discharge space, as shown. This permits the steam to flow in a direct unobstructed course to and through the steam space 5.

The valve ring 6 is seated over the annular discharge space 5 and in order that the steam pressure acting upon the lower side of said ring, may not warp or spring the same between the ribs 8 which hold the ring in seated position, the upper side of said ring is provided with an annular upstanding flange 9 cast integrally therewith.

In addition to the function just set forth for the flange 9, it serves, in connection with the ribs 8, as centering means for the valve ring 6, without securing the latter to the valve seating member 10 as was the case in the patent above referred to. As shown clearly in Fig. 1 the ribs in question are carried by the cylindrical seating member 10, and the outer ends or edges of said ribs abut the inner side of the flange 9 so that horizontal shifting thereof is prevented. Furthermore, the lower ends of the ribs 8 contact with the valve ring 6 to force the same against the seat. These numerous uses of the flange 9 and the ribs 8, are considered highly important features of the present invention since they eliminate additional means which would otherwise be necessary for carrying out the necessary functions.

It will be observed that the ring 6 is entirely unsecured in respect to the valve seating member 10, and that considerable space exists between said ring and member so that 5 the steam may easily escape when the valve pops. Another change which has been made, is to flare the inner edge of the ring 6 as indicated at 11, to even further facilitate the escape of steam between this ring and 10 the spring-pressed seating member 10.

The outer edge of the valve ring 6, rather than being beveled as indicated in my prior 15 device, is formed with a right angular shoulder 12, it having been found that this construction co-operates to equal advantage with the adjusting ring 13, yet that it may be much more easily and less expensively manufactured. Needless to say, the ring 13 may be adjusted and held in adjusted 20 position in any of the well known ways which form no part of the present invention.

Although highly possible that this feature could well be eliminated in some types of the valve, the usual muffling dome 14 is 25 preferably provided, the upper end of said dome carrying the adjusting screw 15 for the valve seating spring 16, the latter being confined within the seating member 10 as usual.

30 From the foregoing, taken in connection with the accompanying drawings, it will be obvious that I have so improved upon the patented device above referred to, as to prevent any possible springing of the 35 valve ring 6 between its points of contact with the ribs 8, and that the flange 9 which performs this reinforcing function, also co-operates with the ribs in question in centering the valve ring, without the necessity of 40 threading or otherwise securing said ring to the seating member 10. The steam pressure beneath the valve ring always maintains the same in contact with the ribs 8 when the valve is opened by the steam pressure 45 and thus no fastening means for said ring is necessary, other than the friction existing between the several contacting parts. It will also be observed from the foregoing, that the steam may escape with greater ease, 50 without any danger of unseating valve ring 6 an excessive extent, that I have simplified and cheapened the construction of this ring without decreasing its efficiency, and that a larger body of steam has been confined beneath the valve ring 6, without the necessity of increasing the area of said valve ring upon which the steam acts, this end 55 being attained by the enlargement 7.

Since probably the best results are obtained 60 from the several specific details shown and described, such details constitute the preferred form of the invention, but I wish it understood that within the scope

of the appended claims, numerous minor changes may well be made.

65

I claim:

1. In a safety valve, a casing having a steam passage and a guide at the delivery end thereof partly obstructing said end to form an annular steam discharge space, a 70 valve-ring seated over and closing said space, a valve-seating member engaged with said guide and passing through said ring but in spaced disconnected relation therewith, a spring for actuating said valve-seating 75 member, and co-acting means on said member and ring for pressing said ring to its seat and centering the ring.

2. In a safety valve, a casing having a steam passage and a guide at the delivery 80 end thereof partly obstructing said end to form an annular steam discharge space, a valve-ring seated over and closing said space, a tubular valve-seating member engaged with said guide and passing through 85 said ring but in spaced disconnected relation therewith, a spring within said member for actuating the same, and co-acting means on said member and ring for pressing said ring to its seat and centering the ring.

90

3. In a safety valve, a casing having a steam passage and a guide at the delivery end thereof partly obstructing said end to form an annular steam discharge space, a 95 valve-ring seated over and closing said space, said ring having an annular stiffening flange on its upper side, a tubular valve-seating member engaged with said guide and passing through said ring but in spaced disconnected relation therewith, a spring for 100 actuating said valve-seating member, and outstanding webs on said member engaging said flange, to center the valve ring, and adapted to press said valve ring to its seat.

4. In a safety valve, a casing having a 105 steam passage and a guide at the delivery end thereof partly obstructing said end to form an annular steam discharge space, a valve-ring seated over and closing said space, said ring having an annular stiffening 110 flange on its upper side, a cylindrical valve-seating member engaged with said guide and passing through said ring but in spaced disconnected relation therewith, a spring for actuating said valve-seating member, and outstanding webs on said member bearing against said valve ring to seat the same and abutting said flange to center said ring.

115

5. A structure as specified in claim 4, the 120 inner edge of said valve ring being flared in the direction of travel of the steam.

In testimony whereof I have hereunto set my hand.

CHARLES F. KRAUT.
